UNITED STATES PATENT OFFICE.

ANTHONY LANZETTA, OF NEW YORK, N. Y.

AEROPLANE.

1,366,471.

Specification of Letters Patent. Patented Jan. 25, 1921.

Application filed November 24, 1917. Serial No. 203,664.

To all whom it may concern:

Be it known that I, ANTHONY LANZETTA, a citizen of the United States, and resident of New York, in the county of New York and State of New York, have invented certain new and useful Improvements in Aeroplanes, of which the following is a specification.

This invention relates to aeroplanes and has for its object means to support or raise any weight by the arrangement of a special plane with deflectors on divisions of the plane which give a certain advantage for air drafts and to avoid overstrain, the opening between each division having beneath it a second plane with stabilizing means surrounding it and comprising hinged planes which may be deflected and held at a desired angle as long as it may be necessary to provide for regulating the plane when off the horizontal position, but which means is released when normal conditions are restored. Means are also provided for directing the machine upward or downward and the rudder is for certain advantageous reasons mounted on the top of the device, and the car for the engine and driver may be located between the stationary planes while floats are provided to sustain the machine upon the water, all of which with other objects and details will be more fully described in the following specification, set forth in the appended claims and illustrated in the accompanying drawings, in which:

Figure 1 is a plan view of the improved aeroplane.

Fig. 2 is a front elevation of the same.

Fig. 3 is a side elevation.

Fig. 4 is an enlarged fragmentary view of the fin.

Fig. 5 is a plan view of the rudder locking means.

Fig. 6 is a side view of the stabilizing control.

Fig. 7 is a plan view of the same.

Fig. 8 is a horizontal sectional view below the upper planes and car.

The device comprises a frame of uprights 10 and horizontal stringers 11 mounted on wheels 12 and carrying a car 13 in which is arranged the engine for the propeller 14 and whatever control mechanism may be necessary for the aeroplane.

Longitudinal bars 15 are supported at the top of the device by the uprights and with the intermediate sheathings 16 comprise a

plane of two sections 17 and 18, with downwardly deflected rear edges, which is stationary and forms the upper plane in case the device is a bi-plane, or it may be in itself 60 a monoplane. Suitable guys and braces connect these members of the frame to form a substantial construction and the rear ends of the plane sections are curved downward to cause buoyancy to float 17 and 18 as the 65 machine moves through the air. As a rear stabilizer, a tail or rudder, such as shown in Fig. 3 may be used and have appropriate steering means.

On the top of the above mentioned plane 70 is a circular raceway 19 in which travel rollers 20 supporting the front and rear ends of the fin 21 while lateral arms 22 at each side of the fin also have rollers 20 at their outer ends to travel in the raceway and retain the fin in its upright position. Depending from the fin and below the raceway is a stem 23 controlled by a hand wheel 24 that is within reach of the aviator and has near its lower end the ratchet wheels 25 and 26 80 with teeth reverse to each other and adapted to be engaged by pawls 27 and 28 pivoted at a fixed point adjacent the ratchet wheels and normally locking the fin rigidly at any desired direction and operated by the 85 pedals 29. When it becomes necessary to change the course of the machine the appropriate pawl is raised out of engagement with its ratchet wheel and the fin may be turned in the direction permitted by the release. 90 As will be seen in Fig. 3 the wheel and stem are located in the entrance of the car and in front of the aviator's seat while the panels 29 are at his feet.

The rollers 20 are introduced into the 95 raceway through an opening 20' and have upper and lower tracks, while the movement of the fin is limited to ninety degrees by stops 21' located around the raceways and intercepting the stems carrying the rollers. One 100 of these stops may be used to cover the opening 20' and confine the rollers within the raceway.

At the lower part of the frame 10 and above the wheels are floats or pontoons 30 105 to buoy the machine on the water in case that it is found desirable to use it as a hydroplane, and the lower surfaces are deflected upward at the front and downward at the rear to facilitate buoyancy in the air or the 110 water.

Beneath the upper planes 17 and 18 and

directly below the opening which separates them is a second stationary plane 31 which like the upper plane is deflected downward at its rear end for buoyancy.

5 Adjacent the lower plane 31 are four pivoted planes, two, 32 and 33 at the front and rear respectively of the machine while the planes 34 and 35 are pivoted to the side of the same. The axis of each of these planes 10 is near its inner side leaving a large sweep at the top edge and they are controlled by levers 36 carrying at their ends suspending rods 37.

The operation of the pivoted planes is 15 shown in Fig. 6 where it will be seen that the lever 36 is pivoted to the bracket 38 of a box 39 adjacent the aviator's seat in the car and its inner end 40 is off set at an angle and has a slot 41. Through the box 39 passes a 20 rack bar 42 with a head 43 at one end and a pin 44 at the other end to connect it with the angular end of the lever 36.

This rack bar is pressed inward by a 25 spring 45 that surrounds it but it is automatically locked by the pawl 46 to hold the planes in their normal horizontal position and the pawl is so retained by a weight 47 hanging from its axle.

If this end of the aeroplane should drop 30 below the horizontal, the weight would cause the pawl to leave the rack bar and the spring 45 would force the bar backward, raising the lever 36 to the position shown in dotted lines and raising the plane 34 to an angle 35 to act as a plane to support the device if it should drop in that direction.

The same construction and arrangement is 40 applied to the planes 32, 33 and 35 to effect an automatic release and for the instant positioning of a plane to retard a sudden abnormal movement and to prevent a lurch which would throw the machine off its horizontal and wreck it.

It is obvious that when the aviator again 45 gets control of his machine and rights it he may push the head 43 and rack bar 42 outward and the plane will resume its normal position. A rod 48 may be used to operate the pawl independently of the weight.

50 In addition to the use of these pivoted planes as a stabilizer means they may also be used as a means for ascending or descending quickly. Assuming that the parts are in a horizontal or neutral position and it is desired to direct the aeroplane upward, then the two side planes are retained in their horizontal position so as to give a larger area of surface and the front and rear planes are allowed to take an inclined rudder position in order to allow the aeroplane an upward movement.

When it is desired to take spiral courses the side planes are released and moved by means of the automatic levers so as to bring

the upward side into a higher operating position while the lower side remains in the horizontal or neutral position.

Should the machine fall into an air pocket and overbalance, the weight and pawl, permitting the operation of the control levers 70 of the side stabilizers, would immediately release and bring the plane back to a neutral position, thereby retarding any abnormal movement and righting the machine.

The fin may be set in any desired direction and held there by the pawls, which with the steering wheels are not only convenient to the aviator but simple and compact. The machine may be widened at each end by the addition of panels to increase its capacity 80 and the number of planes may be increased to make it a triplane.

The location of the fin on the top of the upper plane permits of the ready movement of the pivoted planes and does not interfere 85 with their functions.

It is obvious that other modifications and arrangements of the parts of the device may be resorted to without departing from the essential features above described or from 90 the scope of the appended claims.

What I claim as new is:

1. In an aeroplane, the combination with a frame, a plane divided into sections with a space between them, a lower plane beneath 95 the space, stabilizers at the sides of the lower plane, means for deflecting the stabilizers, means for releasing the deflecting means, and means for checking the deflecting means.

2. In an aeroplane, the combination of a 100 divided plane having an opening between the sections, a lower plane beneath the opening, hinged stabilizers at the edges of the lower plane, a steering fin above the planes, roller bearings supporting the fin, means for 105 automatically raising and deflecting the stabilizing planes, and means for returning the same to their normal positions.

3. In an aeroplane, the combination of a 110 plane divided into two sections by an opening, a steering fin, a raceway at the opening and carrying the fin, a plane beneath the opening, planes hinged around the edges of the same, rods with springs adapted to automatically deflect the hinged planes, and 115 gravity releases for the rods.

4. In an aeroplane, the combination of a divided upper plane, a circular raceway above the same, a steering fin adapted to swing around the raceway, a stem to the fin, 120 locking means for the stem, releasing means for the locking means, a lower plane, and hinged stabilizers around the edges of the latter plane.

5. In an aeroplane, the combination with 125 a top plane of two separated sections and each section having rear deflected edges, of a raceway on the plane, a rudder supported on

rollers adapted to run in the raceway, means below the plane for operating the rudder, a second plane beneath the space between the two top sections, stabilizing planes hinged 5 around the edges of the latter plane, levers controlling the swing of the stabilizing planes, a toothed plunger to rock the lever, a pawl locking the plunger, and a weight for the pawl to cause it to release the plunger 10 when the aeroplane rocks from the horizontal.

6. In an aeroplane, the combination of separated upper planes with their rear edges lower than their front edges, a lower plane 15 having similar lower rear edge and located beneath the opening of the upper plane division, stabilizers around the lower plane, and

means for locking or automatically releasing the stabilizers.

7. In an aeroplane, the combination of a 20 frame, planes at the front and rear of the same, on the same level, separated by an open space and having inclined rear edges; a second frame beneath the open space and carrying a plane with rear inclined edges, steering 25 means for the planes, stabilizing means around the lower plane normally locked, and automatic means for releasing the stabilizing means when the plane leaves its normal position.

ANTHONY LANZETTA.
